UNITED STATES PATENT OFFICE

ARTHUR W. BURKS, OF DECATUR, ILLINOIS

PUMP

Application filed August 16, 1927, Serial No. 213,315. Renewed October 22, 1929.

This invention relates to pumps, and more particularly to pumps of the type comprising a rotary element provided with a series of buckets adapted to impart repeated impulses to liquid passing through a passageway from an inlet port to an outlet port, the passageway being substantially sealed against leakage of the liquid therefrom. Pumps of this general type are disclosed in my Patents 1,619,285 and 1,619,286, granted March 1, 1927.

An object of the invention is to provide an improved pump of this type having a rotor and casing of improved form, and provided with effective means for sealing the fluid raceway or passageway against leakage.

A further object of the invention is to provide a pump which may be cheaply manufactured and readily assembled, and which is adapted for operation through extended periods without adjustment or repair. These and other objects of the invention having to do with the provision of a pump, which is efficient and positive in operation, will become clearer as the description proceeds in connection with the preferred embodiment of the invention shown in the accompanying drawings, wherein

Figure 1 is a front elevational view with a portion of the casing broken away, and

Figure 2 is a vertical sectional view on the line 2—2 of Figure 1.

The casing has a main section 10 forming an interior chamber 11 which receives the rotor 12 having a hub 13 receiving a shaft 14 to which the rotor is secured, as by means of a pin 15. The shaft extends through a bearing 16 to the exterior of the casing where it may have associated therewith any suitable rotating means, such as the pulley 17. The bearing 16 may be sealed against leakage as by means of packing 18 and a gland nut 19 threaded within the bearing 16.

The rotor is of substantially cupped formation having, preferably adjacent its margin, a rim portion 20, the inner and outer surfaces 21 and 22 of which adjacent the rim margin substantially parallel the rotor axis. On the inner surface 21 is provided a plurality of inclined blades 23 arranged in a channel and

forming therebetween an annular series of buckets adapted to receive and impart impulses to liquid which may be introduced into the casing through an inlet port 24 formed in a casing section 10' having a portion 10" fitting within the rotor and provided with a channel 25 opposite the blades, and forming in conjunction with the blades and buckets a fluid passageway. The channel is in substantially annular formation, but does not extend at the top of the casing between the inlet port 24 and outlet port 26, as illustrated in Figure 2, the casing portion 10" being there formed to fit closely against the exposed edges of the blades to prevent liquid from passing the outlet port back to the inlet port. The casing thus serves to deflect fluid from the raceway through the outlet port. To assist in supporting the rotor, the casing section 10" may be provided with a centrally disposed portion 27 providing a bearing for the end of the shaft 14 which extends through the rotor into a bushing 28 fitted closely within the bearing. This portion of the casing may be secured to the casing 10 in any suitable manner, as by the screws 29.

At opposite sides of the blades 23 and of the raceway 25, the casing and rotor have a sealing engagement, for the purpose of making the raceway substantially liquid-tight. The rotor is provided at opposite sides of the casing with the sealing surfaces 30 which are disposed in planes inclined relative to the axis of the rotor, and parallel to one another. These surfaces are spaced along the axis so that they are disposed, respectively, in different radial planes and, as will be observed, they are also disposed at different radial distances from the axis or, in other words, they are readily spaced from one another. These surfaces cooperate with the coacting surfaces 31 upon the casing section 10", and the coacting surfaces are provided with interengaging ribs and grooves 32. This construction permits a relatively close fit between the rotor and casing, which will efficiently seal the liquid within the raceway for extended periods of operation, and any excessive clearance resulting from wear may be taken up by adjustment of the rotor.

As will be noted, the casing has behind the rotor a considerable space into which any liquid seeping from the raceway may pass through an opening 33 in the rotor. The space of the opening 33 will balance the pressure of any escaping liquid against the rotor on opposite sides thereof, and will permit the liquid to pass into the interior of the chamber 11 behind the rotor and lubricate the device.

In the operation of the pump, it will be understood that the fluid passes into the raceway through the inlet port 24, and operation of the rotor by means of power applied to the pulley 17 in a counter clockwise direction will cause the blades 25 to engage the fluid repeatedly as it passes through the raceway and impart impulses thereto. The liquid, as it advances in the raceway, will repeatedly pass into and out of the buckets, the frequency of engagement with the buckets varying in accordance with the back pressure at the outlet. High back pressure at the outlet will tend to lengthen the path of the fluid by increasing the number of times it is subjected to the action of the rotor.

Obviously, the invention is not limited to the details of the construction illustrated and described, and numerous modifications will occur to one skilled in the art without departing from the essence of the invention, which is set forth in the following claims.

Having thus described my invention, what I claim is:

1. A pump comprising a rotor having a plurality of blades forming buckets having mouths opening inwardly toward the rotor axis and a casing making a substantially liquid tight seal with the rotor besides the buckets whereby to form with the buckets a fluid passageway, said casing having inlet and outlet ports.

2. A pump comprising a rotor having a plurality of inwardly directed blades forming buckets having mouths opening inwardly toward the rotor axis, and a casing having a substantially annular channel facing said buckets whereby to form a liquid passageway, said casing having inlet and outlet ports and making a substantially liquid tight seal with the rotor beside the buckets and the raceway.

3. A pump comprising a rotor having a plurality of inwardly directed blades forming buckets having mouths opening inwardly toward the rotor axis, a casing having a substantially annular channel facing said buckets whereby to form a liquid passageway, said casing having inlet and outlet ports and making a substantially liquid tight seal with the rotor beside the buckets and the raceway, and liquid deflecting means interposed between the inlet and outlet ports and closely fitting the exposed edges of the blades to de-

flect liquid from the passageway through the outlet port.

4. A pump comprising a substantially cup-shaped rotor having on the inner face of its rim a plurality of blades directed inwardly and forming inwardly opening buckets, and a casing having a portion fitting within said cup and making a substantially liquid tight seal with the rotor beside the buckets, said casing having inlet and outlet ports.

5. A pump comprising a substantially cup-shaped rotor having a marginal rim provided on its inner face with a plurality of blades directed inwardly and forming inwardly opening buckets, and a casing having a portion fitted within said cup and making a substantially liquid tight seal with the rotor beside the buckets, said casing having inlet and outlet ports, and an annular channel facing said buckets and forming therewith a fluid passageway.

6. A pump comprising a substantially cup-shaped rotor having on the inner face of its rim a plurality of blades directed inwardly and forming inwardly opening buckets, and a casing having a portion fitting within said cup and making a substantially liquid tight seal with the rotor beside the buckets, said casing having inlet and outlet ports, and liquid deflecting means interposed between said inlet and outlet ports and closely fitting the exposed edges of the blades to deflect liquid through said outlet port.

7. A pump comprising a rotor having a rim, a plurality of inwardly directed blades on the inner surface of said rim forming a plurality of inwardly opening buckets and a casing having a portion making a substantially liquid tight seal with the rotor beside said buckets and forming with the latter a substantially liquid tight passageway, said casing having inlet and outlet ports communicating with said passageway.

8. A pump comprising a rotor having a rim, a plurality of inwardly directed blades on the inner surface of said rim forming a plurality of inwardly opening buckets and a casing having a portion making a substantially liquid tight seal with the rotor beside said buckets and forming with the latter a substantially liquid tight passageway, said casing having inlet and outlet ports communicating with said passageway and having an annular channel facing said buckets.

9. A pump comprising a rotor having a rim, a plurality of inwardly directed blades on the inner surface of said rim forming a plurality of inwardly opening buckets and a casing having a portion making a substantially liquid tight seal with the rotor beside said buckets and forming with the latter a substantially liquid tight passageway, said casing having inlet and outlet ports communicating with said passageway, and pro-

- vided with an annular channel facing said buckets, and liquid deflecting means interposed between said inlet and outlet ports and closely fitting the exposed edges of the blades 5 to deflect liquid from the passageway through the outlet port.
10. In a pump, a rotor having a rim portion provided on its inner surface with a plurality of inwardly directed blades forming inwardly opening buckets and sealing surfaces at opposite sides of said buckets.
11. In a pump, a substantially cup-shaped rotor having a rim portion provided on its inner surface with a plurality of inwardly directed blades forming inwardly opening buckets and sealing surfaces at opposite sides of said buckets.
12. In a pump, a rotor having a rim portion provided on its inner surface with a plurality of inwardly directed blades forming inwardly opening buckets and sealing surfaces at opposite sides of said buckets, one sealing surface being disposed substantially radially inwardly and the other radially outwardly from the buckets, said sealing surfaces being inclined relative to the rotor axis.
13. In a pump, a rotor having a rim portion provided on its inner surface with a plurality of inwardly directed blades forming inwardly opening buckets and sealing surfaces at opposite sides of said buckets, said sealing surfaces being inclined relative to the rotor axis and in substantially parallel planes.
14. In a pump, a substantially cup-shaped rotor having a rim portion provided on its inner surface with a plurality of inwardly directed blades forming inwardly opening buckets and sealing surfaces at opposite sides of said buckets, said sealing surfaces being inclined relative to the rotor axis and in substantially parallel planes.
15. A pump comprising a rotor having a plurality of inwardly directed blades forming buckets having mouths opening inwardly toward the rotor axis, a casing facing said buckets whereby to form a liquid passageway, said casing having inlet and outlet ports and making a substantially liquid-tight seal with the rotor at both sides of the buckets and the raceway, and liquid deflecting means interposed between the inlet and outlet ports and closely fitting the exposed edges of the blades to deflect liquid from the passageway through the outlet port.
16. A pump comprising a rotor having a plurality of blades forming buckets having mouths opening inwardly toward the rotor axis and a casing making a substantially liquid-tight seal with the rotor at both sides of the buckets whereby to form with the buckets a fluid passageway, said casing having inlet and outlet ports, the casing and rotor having passageway sealing surfaces at
- opposite sides of the buckets inclined relative to the rotor axis.
17. A pump comprising a rotor having a plurality of blades forming buckets having mouths opening inwardly toward the rotor axis and a casing making a substantially liquid-tight seal with the rotor at both sides of the buckets whereby to form with the buckets a fluid passageway, said casing having inlet and outlet ports, the casing and rotor having at opposite sides of the buckets sealing surfaces inclined relative to the rotor axis, the surfaces at one side of the buckets being substantially parallel to the surfaces at the opposite side of the buckets.
18. A pump comprising a rotor having a plurality of inwardly directed blades forming buckets having mouths opening inwardly toward the rotor axis and a casing having a substantially annular channel facing said buckets whereby to form a liquid passageway, said casing having inlet and outlet ports and making a substantially liquid-tight seal with the rotor at both sides of the buckets and the raceway, the casing and rotor having at opposite sides of the buckets sealing surfaces inclined relative to the rotor axis, the surfaces at one side of the buckets being substantially parallel to the surfaces at the opposite side of the buckets.
19. A pump comprising a substantially cup-shaped rotor having a plurality of blades forming buckets on the inner surface of the rim thereof, said buckets opening inwardly toward the rotor axis at substantially a right angle thereto, a casing for said rotor having a portion making a substantially liquid-tight seal therewith at opposite sides of the buckets, said casing and rotor having at opposite sides of the buckets sealing surfaces inclined relative to the rotor axis.
20. A pump comprising a substantially cup-shaped rotor having a plurality of blades forming buckets on the inner surface of the rim thereof, said buckets opening inwardly toward the rotor axis at substantially a right angle thereto, a casing for said rotor having a portion making a substantially liquid-tight seal therewith at opposite sides of the buckets, said casing and rotor having at opposite sides of the buckets sealing surfaces inclined relative to the rotor axis, with the surfaces at one side substantially parallel to the surfaces at the other side.
- In testimony whereof I have hereunto set my hand.
- ARTHUR W. BURKS.
